UNITED STATES PATENT OFFICE.

GUSTAV A. HARTER, OF CHICAGO, AND JOHN C. SMITH, OF OAK PARK, ILLINOIS.

DESIGN FOR A LAMP-SHADE.

40,266.

Specification for Design.

Patented Sept. 21, 1909.

Application filed July 10, 1909. Serial No. 507,023. Term of patent 7 years.

To all whom it may concern:

Be it known that we, GUSTAV A. HARTER, a citizen of the United States, residing at Chicago, in the county of Cook and State of Illinois, and JOHN C. SMITH, a citizen of the United States, residing at Oak Park, in said county and State, have invented a new, original, and ornamental Design for a Lamp-Shade, of which the following is a specification, reference being had to the accompanying drawing, forming a part thereof.

In this drawing, Figure 1 is a front elevation of the lamp shade, showing our new design, and Fig. 2 a side elevation of the same.

We claim:

The ornamental design for lamp shade as shown.

GUSTAV A. HARTER.
JOHN C. SMITH.
